Specification of Letters Patent.

Patented May 21, 1912.

Application filed March 17, 1906. Serial No. 300,659.

To all whom it may concern:

Be it known that we, JACOB W. LATTIG and CHARLES LANE GOODRUM, citizens of the United States, residing at Rochester, in 5 the county of Monroe and State of New York, have invented certain new and useful Improvements in a Combined Automatic Telephone-Exchange and Fire-Alarm System, of which the following is a specification, reference being had therein to the accompanying drawing.

Our invention relates to combined telephone and fire alarm systems, and has for its object the arrangement of auxiliary fire 15 alarm circuits in connection with an automatic telephone exchange system, so that the fire alarm signals can only be operated under proper conditions, by duly authorized persons or with properly equipped sending 20 devices.

An important feature of the invention is this: that it requires the addition of some special apparatus to the ordinary exchange equipment, but no change in that equipment 25 itself as such.

In the preferred embodiment of our invention, which will be hereinafter fully described, we contemplate the use of that type of apparatus and circuits known in the art 30 as the "Strowger" or "automatic electric" type. The fire alarm attachments are not limited to this type only, but for reasons which will sufficiently appear we consider that type the best for purposes of illustration. In this type of system each subscriber's line terminates on what is called a first selector switch, the control of which is exercised over the line absolutely. In making 35 a call, the subscriber works this switch or machine to effect connection with one after another of a number of auxiliary switches arranged in groups corresponding to the thousands and hundreds digits of the numbers to be selected. The hundreds or 40 connector switches contain calling terminals for the lines, and themselves directly pick out the tens and units digits in obedience to their control. Assuming, for example, that a subscriber desires to talk with another 45 whose number is 4468, he works his first selector to pick out an auxiliary or second selector switch corresponding to 4,000, then obtaining control of that switch he works it in turn to pick out another auxiliary switch

of the order of 400; then by means of this 55 second auxiliary or connector switch he picks out the eighth pair of line-terminals in the sixth row, which belong to line No. 68. Systems of this character, operated in this way, are so well known in the art, and are 60 in such common use, that they require no specific description in order to make them understood by engineers; and we shall not, therefore, either illustrate or describe at length any more than such portions of the 65 general apparatus as pertain to our present invention.

Our invention itself may be briefly stated as follows: Each station from which fire or police signals are to be sent is provided 70 with one or more special sending devices, preferably in the form of make and break wheels somewhat similar to those used in fire alarm telegraphing boxes. In the second selector switch banks at the central 75 office are terminals of special trunks leading to registers adapted to record a call and the number of the calling line. These registers are so arranged that a particular code number must be sent in order to reach them and 80 operate them. False signals are thus prevented. In sending a fire or police signal, the subscriber or other person has only to "pull" the box, that is, start the signal 85 wheels, when the proper impulses will first be sent to work through the first selector switch of the line onto the proper second selector, and so on to the register trunk; then another set of impulses will be sent to work 90 the registers in order to record the number of the line or the station from which the alarm comes.

A number of subsidiary advantages, and many details will appear from the description hereinafter when read in connection 95 with the accompanying drawings forming a part hereof.

In these drawings Figure 1 is a diagram showing a subscriber's station equipped with signal wheels, and a first selector switch at 100 the central office connected to said subscriber's station. Fig. 2 is a similar diagram showing a trunk extending from terminals in the banks of first selector switches to a second selector switch. Fig. 3 is a diagram 105 showing a special fire or police trunk extending from terminals in a second selector switch to a special register switch, having

but a single motion, which we prefer to make a rotary motion.

Referring to the drawings, X is a subscriber's station equipped with our special fire alarm device, by means of which the station can at all times be put into immediate communication with and send an alarm to fire headquarters. The station is connected to the central office by the line wires 1—2, and is provided with a telephone outfit and sender for manual use in calling other stations, shown diagrammatically, and consisting of the following elements: the sender S comprising a reciprocating plunger s having number teeth coöperating with a spring s' on one side, and a spacing or controlling tooth s² coöperating with a spring s³ on the other side. This plunger is supposed to be pulled out any number of teeth desired, then released, so that in its return to normal position the teeth s will engage the spring s' and ground it as many times as there are teeth pulled out. After this number has been sent, the tooth s² engages the spring s³ and grounds it once, thus sending what it called a rotary impulse for controlling the shifting devices of the switches. Both the springs s' and s³ are normally disconnected from ground, so that their branches are dead open. The talking set comprises the usual transmitter T and receiver R, while for incoming signals we provide the usual ringer Q, and controlling both is the switch hook H. The system is common battery, so far as it relates to the supply of current for talking and signaling purposes, and the talking circuit includes the induction coil I, whose secondary, when the switch hook is up, is connected as follows: 1, 3, 4, 5, 6, 7, 8, 9, 2. Included in this secondary circuit is the condenser C, which, when the hook is down, as shown, is also included in the ringing circuit, as follows: 2, 9, C, 8, 10, Q, and ground. The primary talking circuit derives current as follows: 1, 3, 4, 11, 12, 13, 14, T, 15, 16, 9, 2.

In addition to the foregoing parts we provide a ringer button Q', resistance r, and two groups of contact springs h—h', controlled by the switch hook. The functions of these are sufficiently plain from the diagram, and will be further referred to in the statement of operation.

So far, the apparatus at the sub-station is merely that used for talking and for signaling to other subscribers. In addition to this we provide the special fire alarm apparatus shown at x, and comprising a pair of make and break wheels S', S², the former adapted in its rotation to intermittently ground the number one side of line through the spring s⁴, and the latter adapted in its rotation similarly to ground the number two side of line in an intermittent fashion through the spring s⁵. In order that when the fire

alarm wheels S' S² are operating, there shall be no interference from the subscriber's sender, we provide the cut-off x'—x², preferably worked by a cam on the shaft of the make and break wheels (see Fig. 1), in the manner well understood by those familiar with this art, and which we need not describe in detail. When these wheels are started, they send in their impulses in predetermined order, being what we may term "code wheels", in which an important feature of the invention is embodied. This consists in a certain arbitrary arrangement of numbers appropriated to the fire alarm connections, so that only by sending the proper numbers in the proper order can fire alarm headquarters be reached. This will also be further referred to in the statement of operation. At the central office the line wires terminate at contacts n—n' of a cut-off relay N, which is normally deenergized, and which therefore normally connects the line wires to their extensions 17 and 18, which terminate on the wipers 19 and 20.

We shall not enter into detailed description of the general system, or of the switch apparatus as such, since these do not form any essential features of our present invention. In fact, the present invention may be practised with Strowger switches, or with any other desired type of automatic apparatus, provided the same is intended to be operated by means of impulses sent in a predetermined sequence or order. According to the systems we have referred to, we employ for ordinary interconnection between subscribers' instruments switches known as A, B, C, D and G switches. The function of the A switch is to pick out an idle B switch when its line is calling. The function of the B switch is to select the first digit of the required number, and so on. The wipers 19 and 20, in Fig. 1, are carried on the spindle a of an A switch. They normally rest upon contacts 21—22 connected, respectively, to ground by wire 23, and to a magnet M through wire 24, and so to the main battery B'. The magnet M is the controlling magnet for the switch A, which starts the same and keeps it moving until an idle trunk contact is found. This relay M controls the circuit of the motor magnet M' of the switch, and when energized it closes the circuit of said motor magnet and the wiper 25, as follows: B', M', 26, 27, 28, m, 29, 25. This wiper normally rests upon a ground contact 30, forming the terminal of a ground wire 31. When the relay M pulls up it locks itself through the branch wire 32, and the armatures m—m', until an idle or ungrounded contact is reached by the switch, when the magnets M—M' will both lose current.

M² is the release magnet, whose function is perfectly well understood by those skilled

in the art. It controls a detent in the form of a pawl engaging a corresponding ratchet on the spindle *a* and holding the same in the position to which it is turned. This 5 magnet M^2 is energized at the close of a communication when its circuit 33 is completed by the deenergization of the relay N , while the wiper 34 is on a contact 35 closed by the line relay M^4 of a B switch, as will 10 be apparent when the circuits have been further traced. The wires 36 and 37 are, respectively, the line and mate wires going to multiple terminals in the G or connected switches. The wire 38 extends from the 15 wiper 39, which normally rests on the contact 40 connected by wire 41 to the cut-off relay N ; and the wire 38 goes to the test terminals of the G switch, whereby when any other line is calling the station X the 20 cut-off relay N can be controlled. It will be observed that as soon as this A switch in Fig. 1 is started, the wiper 42 passes on to the extension contact 43 forming the terminal for wire 41, and hence the cut-off relay 25 N is connected through wiper 42 so as to be controlled by the relay M , as long as the switch A is moving. In other words, the contacts $n-n'$ are drawn in to disconnect the line wires 1-2 from the wipers 19 and 30 20, while the A switch is passing around to find an idle trunk. By this means clicks are avoided in other lines and their trunks which are connected.

Referring to Fig. 2, we have here a B 35 switch, whose spindle *b* is turned step by step through the agency of the motor magnet M^3 . We shunt this and some of the other magnets with condensers C' , for the purpose of taking up the line discharge and 40 so quickening the action. The spindle *b* carries wipers 47 and 48 from terminals of the talking circuits 49 and 50 of the switch. These wires are connected through the back contacts of a cut-off relay N' to the wires 45 45 and 46 leading to terminals 21^a and 22^a in the A switch banks. When the A switch is turned to an idle trunk, the wiper 25 comes 50 on a contact 25^a connected by wire 51 to a contact 52 in the B switch bank, upon which 55 normally rests the wiper 54 connected by wire 55 around cut-off relay N' and so to main battery B' . The first result effecting a connection with the B switch shown, therefore, is to energize its cut-off relay, 60 which pulls in the armatures $n-n'-n^2$, connecting the wire 45 to the wire 56, leading to relay M^4 , and battery. The cut-off relay N of the A switch having become deenergized, the intermittent grounding of line at 65 the station X will energize the relay M^4 correspondingly to open and close the circuit 57 of the motor magnet M^3 , and so step the spindle *b* around to the desired contact. (We should state that our switches shown herein do not have any vertical motion, but

merely a rotary motion.) The single ground on the mate side 2 of line which follows the set of impulses over the wires 1, produces the energization of the double-wound relay M^5 , through its windings m^5 . 70 This relay pulls up and by means of its armature m^6 connects the test wiper 53 to the winding m^8 of said relay M^5 through relay M^8 and locks up relay M^5 so long as wiper 53 finds ground. When wiper 53 fails to find ground relay M^5 drops back 75 and grounds wiper 53 through relay M^8 over the circuit which includes the circuit closer n^2 relay M^8 to ground. The energizing of the relay M^5 also cuts off the ground from the motor magnet and at the same time closes the circuit of magnet M^6 , whose armature controls the escape of the ratchet-wheels which effect the retrograde movement of the usual selector switch which 80 movement selects an idle trunk to the fire alarm and signal receiving apparatus as heretofore explained. The release magnet for this switch is marked M^7 , and is controlled by the relays M^8 and M^4 . That is to say, the line relay M^4 can operate the release magnet M^7 when the double-wound magnet M^5 is locked up, since the ground from armatures m^7 is then on the wire 58. The relay M^4 at the same time controls ground back over wire 59 and the contact 60, wiper 34, and the release magnet M^2 of the A switch. This clearing-out effect is 90 only produced when both sides of the line are grounded simultaneously, and this occurs when the subscriber finally hangs up at the end of a communication, ground being then put on through the branches 3 and 9 and the set of springs h' .

Assuming we have an exchange of not 105 over ten thousand subscribers, the B switch is used to select thousands, and the operation we have so far traced is sufficient to understand the fire alarm invention *per se*. Certain trunks are appropriated to the fire alarm service, say, for instance, trunks one thousand, or more if required. The B switch having come on the one thousand trunk, connection is thereby established with the fire alarm circuits shown in Fig. 3. 110 These comprise trunk wires 61-62, leading from the bank terminals 65-66 of the B switch to the special fire alarm trunk relays M^9-M^{10} . These are controlling relays only. That is, they have no particular function 115 in completing the talking circuit, but work signals. We do not wish to limit ourselves by these to the exclusion of talking circuits, for it is obviously necessary to be able to talk to fire headquarters as well as to signal. 120 This, however, involves no more than the ordinary operation of our systems, hence the present description has to do particularly with the method of registering the calls. Having got through the switch to the trunk 125 130

61—62, successive grounds coming on the line wire 1 cause impulses in the trunk 61 and through the relay M^9 . This relay controls an auxiliary relay M^{11} , which in turn controls the trunk wires 67—69 proceeding from the telephone central station to the fire headquarters. On the other hand, the relay M^{10} controls an auxiliary relay M^{12} , which in turn controls the trunk wire 70.

10 At fire headquarters we provide a switch F with a spindle f having but one pair of wipers f' — f^2 . These wipers pass over contacts 71—72—73—74—75—76—77 and so on, the contacts 75—76—78—79 and 80 being connected to register magnets adapted to record the number of the station calling. The wiper f^2 merely closes a local circuit 81 containing an alarm bell 82, and a battery B^{11} , this local circuit being maintained closed

15 until the switch is restored. The switch F at fire headquarters is operated by means of a motor magnet M^{13} and is released by means of a magnet M^{14} . The former is included in the trunk 70, and the latter in a ground branch from the trunk 69.

The operation of our system may now be understood. Assuming a subscriber wishes to send a fire alarm, he "pulls" the box attached to his telephone. That is, winds up 30 the mechanism and starts the wheels S' S^2 rotating in the direction of the arrow. The first effect of this is to open the switch contacts x' — x^2 , and the next is to ground the wire 2 at the spring s^5 . This closes the 35 circuit of a controlling magnet M of the A switch, which thereupon starts that switch to rotating to find an idle B switch. When the wipers 19—20—25, etc., have come upon the trunk of an idle B switch, the A switch 40 stops, as heretofore stated, and the B switch is then ready to be controlled, its cut-off relay N' taking current through the following circuit: B' — N' —55—54—52—51—25—25—29— m , and ground. It will be observed 45 that while each switch is being operated its wipers are cut off. The next thing that happens is the grounding of the number one side of line by the wheel S' , which turns the B switch spindle one step to a one thousand 50 trunk,—61—62. The B switch then becomes quiescent, owing to a succeeding impulse from the number two side of line, and succeeding impulses due to the wheel S' coming through wires 1, 17—45—49— and 61 to the 55 relay M^9 , which we have called a special fire alarm trunk relay. As yet this has done nothing. From this point onward, the relay M^{10} does the work of stepping, and the relay M^9 does the work of controlling. That 60 is to say, the wheel S' having automatically selected the special fire alarm trunks, it requires a certain combination of impulses coming alternately over the two sides of the line to the fire alarm trunk relays M^9 and M^{10} , to set the register step by step at fire

headquarters, and at each step when it is properly set, to send the necessary impulse to operate the register. This combination makes it absolutely impossible for any one to send in false signals. Without it mischievous persons would undoubtedly annoy the fire department without the slightest possibility of discovery, inasmuch as they could not be identified by the number sent. With the arrangement shown in Fig. 3, 70 after the connection is made through to the switch F, it takes two impulses over the mate or number two side of line from the wheel S^2 to reach the first register magnet Z. Such impulses affect the relay M^{10} , and by its means the relay M^{12} , and by its means through the trunk wire 70 the stepping magnet M^{13} , by which the spindle is set around two steps. This brings the wiper f' on the contact 75. With the contact so placed, if the station calling contains five digits, an impulse or impulses must come over number one side of line from the wheel S' , in order to set the first register Z to the desired digit. One more impulse over the 75 number two side of line will set the switch around to the next register magnet Z' , and then must come further impulses over the number one side of line to work that magnet. Then it takes two more impulses to 80 reach the next register magnet, and if a false signal is sent with only one impulse at this point, the succeeding impulse over the number one side of line will merely close the following release circuit: B' —67— f' —77—69— M^{14} . Hence the alarm would not be given. If, however, the necessary double impulse come in on the magnet M^{13} , the following impulses over the number one side of line will pass through wiper f' to the contact 78 and the magnet register z^2 . We have shown the succeeding register magnets z^2 — z^1 on succeeding contacts, but obviously we may introduce as many code changes in these contacts as we please. The 85 signal having thus been sent, when the wheels run down the contacts x' — x^2 are closed at the station X, and at fire headquarters a telephone may be bridged across the wires 90 61—62 in any well known or suitable manner, so that conversation can then be carried on between the calling subscriber and the fire chief or his subordinates. At the close 95 of the conversation, when the subscriber hangs up, he momentarily grounds both sides of his line. This produces momentarily impulses through both relays M^9 and M^{10} in Fig. 3, and when both pull up, both auxiliary relays M^{11} — M^{12} will pull up, closing the release circuit as follows: B' —84—69— M^{14} , and ground. At the same time the two relays M^9 — M^{10} close a back release circuit as follows: B' —86—87—88 (then into Fig. 2), 53—89— n^2 — M^8 , and ground. M^8 in turn closes the circuit 90 of the re- 100 105 110 115 120 125

lease magnet M^1 of the B switch, and also grounds the back release wire 59 connected by way of 60—(then into Fig. 1), 34—release magnet M^2 of the A switch, and to battery, by way of 33. All the apparatus is thus restored, and ready for another call.

We are aware that many details of our invention may be changed, and many modifications resorted to without altering the underlying principles or the spirit of the invention. All such changes and modifications we claim as our own, and as within the scope and purview of our invention.

Having thus described our invention, what we claim and desire to secure by Letters Patent, is:—

1. In a combined telephone and special service system, subscribers' lines, automatic switches adapted to be controlled by said lines to effect inter-connection therebetween, signal apparatus associated with said switches and special calling devices at one or more subscribers' stations for effecting connection through the automatic switches with said signal apparatus and to automatically operate said signal apparatus when the connection therewith is established.

2. In a combined telephone and special service system, a plurality of subscribers' lines, automatic switching devices for inter-connecting the same, signal apparatus associated with the automatic switching devices, and special means associated with one or more of said subscribers' lines for sending a series of pre-arranged impulses adapted to operate the switching devices, and by means thereof to connect with and actuate the said signal apparatus.

3. In a combined telephone and special service system, a plurality of subscribers' lines, automatic switching devices controllable over the lines for effecting inter-connection between the said lines, a special signal apparatus connected with said switch, and special signal sending means associated with one or more subscribers' lines and comprising mechanical circuit changers, movable to produce the predetermined signal necessary to select a signal apparatus at central and operate the same.

4. In a combined telephone and special service system, comprising a plurality of subscribers' lines, automatic switches controllable thereover to effect inter-connection therewith, a special receiving apparatus associated with the switches and special sending devices associated with one or more of the subscribers' lines, adapted to send only the code number necessary to select the receiving apparatus and the number or code indication of its line for record by the receiving apparatus.

5. In a combined telephone and special service system, subscribers' lines and automatic telephone exchange apparatus for in-

terconnecting the same, together with special signal receiving means accessible only through the telephone exchange apparatus, and signal wheels associated with one or more of the subscribers' lines, having teeth arranged to send code numbers over the lines to select the special receiving means, and to record thereon the line numbers calling.

6. In a combined telephone and special service system, subscribers' lines, automatic switches for inter-connecting the same, special signal receiving means associated with said switches, and special sending devices at one or more of the subscribers' lines, said special sending devices being adapted to automatically send impulses over opposite sides of the lines in different combinations, to automatically connect with the special receiving means and identify the calling line in said receiving means.

7. In a combined telephone and special service system, and in combination with automatic exchange apparatus and subscribers' lines connected thereto, signal devices associated with one or more of the subscribers' lines, said signal devices having engaging projections differently spaced and adapted to automatically send differently combined impulses over opposite sides of the line, and a receiving apparatus connected with said exchange apparatus, adapted to receive and record the identifying numbers or impulses of said devices.

8. In a combined telephone and special service system, subscribers' lines, automatic exchange apparatus, special signal receiving apparatus, accessible only through the telephone exchange apparatus, and signal devices associated with one or more of the subscribers' lines, said signal devices having engaging devices necessary to connect said line with the special signal receiving apparatus and also to send special impulses over opposite sides of the line to cause said special receiving apparatus to operate and identify the calling line.

9. In a combined telephone and special service system, in combination with automatic exchange apparatus and subscribers' lines connected thereto, a receiving apparatus connected with said exchange apparatus, adapted to receive and record signals from one or more of said subscribers' lines, and a signal apparatus embodying circuit breaker wheels adapted to operate successively on opposite sides of the line to produce predetermined signals and operate said signaling receiving apparatus in connection therewith as established.

10. In a combined telephone and special service system, subscribers' lines, automatic switches adapted to be controlled by said lines, to effect inter-connection therebetween, signal apparatus associated with said switches, and means at one or more subscrib-

ers' stations for effecting connection through
automatic switches with said signal appa-
ratus, said means including circuit breaking
wheels adapted automatically to send suc-
5 cessive impulses over opposite sides of the
line to operate said receiving apparatus and
identify the calling line.

In testimony whereof we affix our signa-
tures in presence of two witnesses.
